(57) **CLAIM**

The ornamental design for a coffee dispenser with an enclosed brewing unit for coffee capsules, as shown and described.

DESCRIPTION

FIG. 1 is a right hand elevation view of the coffee dispenser with an enclosed brewing unit for coffee capsules that comprises my invention;

FIG. 2 is a left hand elevation view thereof;

FIG. 3 is a top view thereof;

FIG. 4 is a front view thereof;

FIG. 5 is a rear view thereof; and,

FIG. 6 is a front perspective view thereof.

The broken lines depict environmental subject matter only and form no part of the claimed design.
